WITNESS:

R. R. Lerevers, INVENTOR
BY Victor J. Evans
ATTORNEY

UNITED STATES PATENT OFFICE.

ROBERT R. LEREVERS, OF CAIRO, ILLINOIS.

SOLE-CHANNELING CUTTER.

1,392,422.

Specification of Letters Patent. Patented Oct. 4, 1921.

Application filed January 28, 1921. Serial No. 440,694.

To all whom it may concern:

Be it known that I, ROBERT R. LEREVERS, a citizen of the United States, residing at Cairo, in the county of Alexander and State of Illinois, have invented new and useful Improvements in Sole-Channeling Cutters, of which the following is a specification.

This invention relates to improvements in needle plates for sole sewing machines, the 10 principal object of the invention being to provide a channel cutting knife with means for moving the same into inoperative position when it is desired to use the machine for sewing rubber or composition soles.

15 Another object of the invention is to provide locking means for holding the knife in either its operative or inoperative position.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a plan view of the needle plate constructed in accordance with my invention.

Fig. 2 is an edge view thereof.

Fig. 3 is a view of the cutting member.

Fig. 4 is an enlarged section on line 4—4 35 of Fig. 1.

In these views 1 indicates the needle plate which is secured to the machine by the usual screws 2 and is provided with the usual elongated needle hole 3.

40 As is well known a cutter is used on needle plates for sewing leather soles on shoes, the cutter forming a channel for the thread. When rubber or composition soles are used, however, it is not possible to channel said 45 soles so that the needle plate carrying the cutter must be removed and a plate without a cutter substituted. This action of substituting one plate for the other takes up a great deal of time and it is the object of my

50 invention to provide means for moving the cutter into inoperative position when the machine is to be used for sewing rubber or composition soles.

55 In carrying out my invention I provide a slot 4 in the plate which extends longitudinally thereof adjacent one of its side edges,

as shown. This slot accommodates the cutter 5 which consists of the shank 6 and the cutting head 7 which is connected with the shank at the upper edge thereof so that the 60 cutter is above the plane of the plate. This head is located at the front end of the shank and this end of the shank is provided with a pin 8 which is adapted to engage a hole 9 formed in the plate and forming a continuation of the slot, the pin occupying this hole when the cutter is in operative position. The shank is also provided with a hole 10 for receiving the end 11 of the locking bar 12 when the cutter is in operative position. 70 This locking bar is slidably supported by the needle plate by passing through the bearing 13 on said plate. This locking bar passes transversely across the plate and has its rear end provided with a handle portion 14 which 75 also acts as a stop for limiting the outward movement of the bar and its other end is of substantially U-shape. The part 11 is adapted to pass through a hole 15 formed in the side of the needle plate with which hole 10 80 in the cutter will register when the cutter is in operative position. When this occurs the locking bar is moved toward the left so that its end 11 will pass through the hole 10 and thus lock the cutter in operative position 85 with its cutting head in alinement with the needle hole 3. In this position the pin 8 will engage the hole 9 so that the cutter is firmly held in operative position. When the device is to be used for sewing rubber or 90 composition soles the locking bar is moved toward the left so as to free the cutter and then said cutter is moved to the rear end of the slot and the locking bar moved back toward the left so that its end 11 will engage 95 the cutter at the junction of the pin 8 with the shank and thus hold the cutter in inoperative position. The main part of the locking bar resting upon the edge of the shank of the cutter will help to hold the same 100 against movement.

It will thus be seen that the cutter can be easily and quickly moved into operative or inoperative position so that the machine can be used for sewing leather soles upon shoes, 105 the cutter forming the channel for the thread or by moving the cutter into inoperative position the machine can quickly be utilized for sewing rubber or composition soles upon shoes.

110 The cutter can be changed from operative to inoperative position and vice versa with-

out the use of any tools and when the cutter has become worn it can be easily replaced by a new one, thus saving the expense of an entirely new plate.

5 It is thought from the foregoing description that the advantages and novel features of my invention will be readily apparent.

I desire it to be understood that I may make changes in the construction and in the 10 combination and arrangement of the several parts, provided that such changes fall within the scope of the appended claims.

What I claim is:—

1. A needle plate of the class described 15 having a longitudinally extending slot there- in and openings communicating with the slot, a cutter including a shank and a cutting head, the shank sliding in the slot, said shank having an extension for engaging one 20 of the openings when the cutter is in operative position and an opening for register- ing with the other opening in the plate and a locking bar slidably mounted on the plate and having a part for passing through the 25 registering openings for holding the cutter in operative position and for engaging the

extension for holding the cutter in inoperative position.

2. A needle plate of the class described provided with the usual needle slot and having means disposed longitudinally, relative to said plate, whereby a cutter in correlation with said means is slidable into operative and into inoperative position, said means and said cutter co-acting to limit the forward movement of the cutter to a position where the cutting head of said cutter is in alignment with the needle slot in the plate, and within the body of said plate, and means for holding the cutter in operative and in inoperative position.

3. In a needle plate of the class described provided with the usual needle slot, means angularly disposed, relative to said needle slot, whereby a cutter in correlation with said means is movable into operative and into inoperative position, independently of any movement of said plate, and means for holding the cutter in operative and in inoperative position.

In testimony whereof I affix my signature.
ROBERT R. LEREVERS.
